UNITED STATES PATENT OFFICE.

ANGELO HEILPRIN, OF PHILADELPHIA, PENNSYLVANIA.

SUPPLEMENTAL CAR-STEP.

SPECIFICATION forming part of Letters Patent No. 634,618, dated October 10, 1899.

Application filed August 7, 1899. Serial No. 726,352. (No model.)

To all whom it may concern:

Be it known that I, ANGELO HEILPRIN, a citizen of the United States, residing at Philadelphia, in the county of Philadelphia and 5 State of Pennsylvania, have invented new and useful Improvements in Supplemental Car-Steps, of which the following is a specification.

This invention relates to certain new and useful improvements in supplemental steps for cars, the object being to provide the ordinary steps of a car with an additional step, which when not in use is held in a vertical position beneath the lower permanent step and when not so positioned may be lowered from 15 the car-platform, the construction and arrangement providing a step which when not in use will not project beyond the lower fixed step of the car and which may be operated when the gate of the car-platform is opened or may 20 be disconnected therefrom, so that the step will remain in a vertical position when the gate is opened.

In carrying out my invention I provide the car-platform with hangers or other means for 25 supporting the fixed steps and for pivotally connecting thereto a supplemental step, the support and step having means suitably connected thereto which when brought into play will lower the supplemental step and hold it 30 in a horizontal position, as will be hereinafter fully set forth, and specifically pointed out in the claims.

In the accompanying drawings, Figure 1 is a perspective view showing one form of my 35 improved car-step applied to a car. Fig. 2 is an end elevation showing the supplemental step raised. Fig. 3 is a detail view showing a front elevation of the step and means for attaching springs which raise the step to a 40 vertical position. Fig. 4 is a detail sectional view on the dotted line 4-4 of Fig. 3. Fig. 5 is a rear elevation showing means whereby the supplemental step is actuated from the 45 gate of the platform. Fig. 6 is a side view of one form of the step-operating mechanism shown in Fig. 5.

In the drawings, A indicates the platform of a car, which is provided with the usual steps *a a*, the frame which supports the step 50 being extended beneath the lower step to provide hangers *b b*, in which is secured the rod

or shaft *b'*, upon which a supplemental step B is secured, so as to turn thereon. The step B is constructed to have on the side opposite its tread an arm *B'*, and the other end of the tread may have a similar arm *B''*, which coacts with the arm *B'* to maintain the auxiliary step when lowered in a horizontal position. The ends of the arms *B' B''* can abut against a rod *b''*, carried by the hangers, and the bent 60 ends or stops on the arms will engage the frame. A series of coiled springs *b''* are positioned upon the rod *b'*. One end of the springs bears against the bar *b''*, while the other end engages the under side of the step and may be 65 permanently attached thereto. The tendency of the springs is to hold the step B in a vertical position beneath the lower fixed step *a*.

At a suitable point upon the guard-rail of the platform I pivot a lever C, one end being 70 connected by a rod *c* to the arm *B'*. This lever may have a suitable lock or catch and, if desirable, a spring which tends to lower the rod *c*, attached to the step, said spring coacting with the springs *b''* on the supporting-rod 75 *b'*. The hangers, which depend beneath the lower fixed step and to which the supplemental step is connected, are of such configuration that the projecting portion on the ends of the arms will abut against the inner sides 80 of the hanger when the supplemental step is in a horizontal position and will clear the hangers when the step is swung upward.

To operate or lower the supplemental step from the vertical position, (shown in Fig. 2 of 85 the drawings,) the hand-lever C is depressed and locked in the position shown in Fig. 1, which movement is contrary or against that exerted by the spring and brings the step to a horizontal position, in which it is held by 90 the lock. It is only necessary to release the lock to permit the step to assume a vertical position.

In Figs. 5 and 6 of the drawings I have shown means for operating the auxiliary step by a 95 movement of the platform-gate, and in such instance the platform-gate D may be mounted to swing independently of a standard D', and when so mounted the standard D' is supported so as to have a rotary movement in its bearings and carries at its lower end a gear, preferably a beveled pinion *d*, which meshes with 100

a gear or similar pinion d^2 , which is provided either with an outwardly-projecting arm e or a hub e' . When the arm e is used, the supplemental step may be connected thereto by a rod E , and where it may be desirable to use a flexible connection such connection is attached to the hub or drum e' and to the step. With the construction shown when the gate is closed the auxiliary step will be brought to a vertical position, and when the gate is opened it will be lowered. The standard D is provided with a suitable catch or lock f , and when one end of the same is pressed toward the standard a pin carried by the other end will be disengaged from the hinge of the gate, so that the gate may swing independent of the same and so that the gate can be opened without operating the step. This is desirable in cases where the cars stop opposite a platform, which platform is usually built on a level with the lower fixed step.

The supplemental step is applicable to cars as now constructed, and where supports for the fixed step of a suitable type are not present brackets or hangers may be connected thereto. The construction is such that there are no projecting parts which are liable to engage the clothes of a person getting on or off the car, and the step when raised does not add to the width of the car. The invention is also applicable to open or side-entering street-cars, as the supplemental step may be readily applied thereto and operated either from the front or rear platform.

The invention is susceptible of modifications which can be readily made by a skilled

mechanic without departing from the scope of the claims.

I claim—

1. In combination with a car-platform and its step or steps the lower of said step or steps having depending means and means for pivotally connecting therewith an auxiliary step, a spring positioned between the depending supporting means and mounted thereon so as to hold the auxiliary step in a vertical position, means carried by the step for limiting its movement beyond a horizontal position when lowered and means for manually operating the step against the action of the spring and holding the same in a horizontal position, substantially as shown. 40

2. The combination with a car-platform and its steps, of an auxiliary step pivotally supported and provided with means for maintaining the same in a vertical position beneath the lower fixed step of the platform, means connected to the auxiliary step to one side of its pivot and extending upward therefrom a rotary standard having at its lower end means for engaging and actuating the auxiliary step, a gate mounted on the standard so as to move therewith or independent thereof and a lock for connecting or disconnecting the gate and standard. 55

In testimony whereof I have hereunto set my hand in presence of two subscribing witnesses.

ANGELO HEILPRIN.
